CARTON SEVERING INSTRUMENTALITY
Angelo Magnatta, 2075 N. Kennison Drive,
Toledo 9, Ohio
Filed Oct. 13, 1960, Ser. No. 62,499
5 Claims. (Cl. 30—2)

This invention relates to cutting or severing devices and more particularly to a manually usable cutting device or instrumentality especially adapted for severing or cutting the walls of a package or carton in a particular manner to facilitate the handling and displaying of the contents of the carton.

In the packing industry and more especially in the packaging of can goods such as canned foods in cartons, it has become a conventional practice to pack the cans in a carton fashioned of cardboard or paperboard arranged in two tiers of, for example, twenty-four cans in each tier. It has been proposed and has been practiced to a limited extent to sever the side walls of a cardboard carton at two regions spaced respectively from the top and bottom of the carton whereby the bottom and top sections of the carton become, in effect, trays for supporting the can goods for display and stock purposes, there being twenty-four cans in each tier in each tray formed by thus severing a carton containing forty-eight cans.

Through this method of severing the side walls of a carton or package at regions spaced from the top and bottom, the center band portion between the severed regions may be discarded. Difficulties have been encountered in severing the side walls of a carton as no satisfactory means is available for severing the side walls at proper distances from the top and bottom surfaces of the carton with assurance of obtaining a proper severing providing a clean edge for the carton trays for display purposes.

The invention embraces the provision of a carton cutting or severing instrumentality provided with a simple, yet effective, gage means for facilitating severing a carton wall at predetermined vertical distances from the bottom and top without inverting the carton and the severing operations performed while the carton is resting upon a suitable table, conveyor or other support.

Another object of the invention resides in the provision of a carton cutting instrumentality embodying dual cutting blades or severing devices arranged in spaced apart relation and at predetermined distances from gaging surfaces formed on the instrumentality whereby the side walls of a carton may be severed at upper and lower regions at equal distances from the planes of the top and bottom of the carton assuring smooth, clean severed edges of the carton wall whereby the same present a neat appearance for stock display purposes as well as to facilitate subsequent handling of the can goods in each tray-like section provided by the top and bottom components of the carton through the severing operations.

Another object of the invention resides in a carton cutting instrumentality having dual cutting blades which are adjustable into a body or handle construction from a position of use to a stored position to minimize the liability of an operator inadvertently being cut by the instrumentality when the same is not in use.

Still another object of the invention resides in a carton cutter having dual cutting blades cooperating with a gage block or means arranged at a convenient angle to the handle of the device or instrumentality, the cutting edges of the blades being arranged in relation to the handle and the gage block or projection so as to obtain an oblique severing of a carton wall by the cutting blades, the gaging means provided with a facing of material which will withstand usage without appreciable wear.

Another object of the invention resides in the provision

2

of means for locking or securing either or both of the blades in an operative or severing position or in an out-of-use position.

Another object of the invention resides in the provision 5 of a resilient means associated with a cutting blade in combination with manual means for adjusting the cutting blade, the blade being normally biased in one direction under the influence of the resilient means.

Another object of the invention is the provision of a 10 carton cutting instrumentality wherein the body or handle components are fashioned of plastic or other lightweight material which may be molded or cast to facilitate volume production at low cost.

Still another object of the invention resides in a means 15 for securing or locking a severing blade in adjusted positions whereby the blade may be projected from the holder or handle a desired distance to effect a complete severing of the wall of a container without contact or engagement with the cans or product packed in the container.

Another object of the invention resides in a carton cutting instrumentality in which the cutting blades are readily replaceable in event they become worn or dull and replacement effected without the use of tools.

Further objects and advantages are within the scope 20 of this invention such as relate to the arrangement, operation and function of the related elements of the structure, to various details of construction and to combinations of parts, elements per se, and to economies of manufacture and numerous other features as will be 25 apparent from a consideration of the specification and drawing of a form of the invention, which may be preferred, in which:

FIGURE 1 is a plan view of one form of cutting instrumentality of the invention illustrated in a position 30 of use for severing a lower wall region of a carton;

FIGURE 2 is a plan view of the cutting instrumentality in an inverted position of use for severing the upper side wall region of a carton;

FIGURE 3 is an elevational view of the construction 35 shown in FIGURE 1, portions of the handle being illustrated in section;

FIGURE 4 is a transverse sectional view taken substantially on the line 4—4 of FIGURE 1;

FIGURE 5 is a detail sectional view taken substantially 40 on the line 5—5 of FIGURE 1;

FIGURE 6 is a transverse sectional view taken substantially on the line 6—6 of FIGURE 1;

FIGURE 7 is a detail sectional view taken substantially 45 on the line 7—7 of FIGURE 1;

FIGURE 8 is an isometric view of a wear plate forming 50 a component of the construction;

FIGURE 9 is an isometric view of a carton and the cutting instrumentality of the invention illustrating the method of severing the upper side wall region of a carton;

FIGURE 10 is an isometric view showing the method 55 of using the cutting instrumentality for cutting or severing the lower side wall region of a carton;

FIGURE 11 is an elevational view of the cutting instrumentality in a position of use as shown in FIGURE 9 60 illustrating the manner of use of the gage block and the position of a cutting blade in relation to the top of the carton;

FIGURE 12 is a detail view of one of the cutting blades;

FIGURE 13 is a plan view partly in section illustrating 65 a modified form of the invention;

FIGURE 14 is a transverse sectional view taken substantially on the line 14—14 of FIGURE 13; and

FIGURE 15 is a transverse sectional view taken substantially 70 on the line 15—15 of FIGURE 13.

While the carton severing instrumentality of the invention is particularly adaptable for use in severing the

upper and lower side wall regions of a carton containing cans of food or other product, it is to be understood that the instrumentality may be used generally for severing walls of any type of carton containing any type of product but is particularly adaptable for use in severing the side walls of a carton at predetermined distances from the top and bottom of the carton whereby the top and bottom sections of the carton become supporting trays of identical character suitable for containing and displaying each tier of cans or other product.

Referring to the drawings in detail, and initially to the form of the invention illustrated in FIGURES 1 through 11, the cutting instrumentality is inclusive of a body 10 formed with a head or blade supporting portion which is provided with a handle or grip portion 12 and a gaging means or portion 14. In the embodiment illustrated the handle portion 12 is fashioned of two sections 16 and 18, the upper section 16 terminating in a portion 17 in which the cutting blades are accommodated, the lower handle section 18 being formed as an integral component of the head 10 and the gage means 14.

The body and handle components of the construction may be fashioned of any suitable plastic or resinous material such as ethyl cellulose (marketed under the trade name Ethocel), or these components may be cast of suitable material preferably of light weight such as aluminum. The sections 16 and 18 of the handle portion of the construction are adapted to mate in the manner shown in FIGURE 6. The handle sections are fashioned so that the mating planes lengthwise of the handle portion are illustrated at 19, 20 and 21, the offset provided by this configuration serving to properly align the handle sections lengthwise for ease of assembly.

The handle sections are secured together by two rivets 24 and 25 as shown in FIGURE 3, the interior of the sections being of hollow configuration to provide a device of minimum weight. The section of the head or body 10 at the forward terminus of the handle section 18 is formed with a thickened portion 28, an offset section 30 of the body terminating in an angularly extending projection or block 32 which provides a gage means for properly positioning the cutter at predetermined distances from the top and bottom of a carton during severing operations.

The regions 17 of the section 16 adjacent the head portion are provided with recesses or slots to accommodate the cutting blades. The blades are spaced vertically as viewed in FIGURE 3 and in side-by-side relation as viewed in FIGURE 4. The region 17 of the handle section 16 is formed with a lengthwise recess accommodating a cutting blade 34 fashioned with a cutting edge 35 as shown in FIGURE 1.

Preferably disposed or embedded in the section 16 adjacent the cutting blade 34 are longitudinally extending metal insert means 36 which form suitable ways or guides in which the cutting blade 34 is slidably accommodated or mounted.

The body portion 17 is formed with a second lengthwise recess accommodating a second cutting blade 38 fashioned with a cutting edge 39. Molded or embedded in the section 16 adjacent the recess accommodating the blade 38 are longitudinally extending metal insert means 40 which provide ways or guides slidably accommodating the cutting blade 38. The portion 17 of the handle section 16 and the head portion 10 are each provided with pairs of parallel slots 42 and 44 through which extend headed bolts 46 and 48.

The bolt 46 extends through the slots 42 and through a circular opening 49 in the blade 34, the threaded end region of the bolt 46 accommodating a knurled nut 50. The bolt 48 extends through the slots 44 and through a circular opening 49 in the blade 38. The threaded region of the bolt 48 is provided with a knurled nut 52. The slots 42 and 44 extend lengthwise of the handle construction and by releasing the knurled nuts 50 and 52

the bolts may be adjusted or moved lengthwise in the slots to project the blades 34 and 38 to a position of use or retract them into the handle section to an out-of-use position. When they are projected forwardly of the section 16, they are in position for severing a carton.

By manipulation of the knurled nuts 50 and 52 the cutting blades may be locked either in a position of use or in a retracted or out-of-use position. One of the blades 34 is illustrated in FIGURE 12 and both blades are of identical shape and size, each blade having a circular opening 49 to accommodate the adjacent bolt. As will be apparent from FIGURES 1 and 2, the cutting edges of the blades are arranged at an angle of approximately 45° with respect to a wall of a carton to be severed.

The offset portion 30 of the head 10 is provided with a projecting gage block or portion 32 preferably extending at an angle of about 45° to the longitudinal axis of the handle portion 12 as shown in FIGURES 1 and 2. The projection or block 32 provides a gaging means for guiding the cutting blades during carton severing operations. Embedded in the portion 30 and in the projection 32 is a metal wear plate 56 of generally L-shaped configuration, the plate being illustrated in detail in FIGURE 8.

The vertical leg portion 58 of the wear plate is embedded in the vertical face region of the offset portion 30 and the horizontal leg portion 60 is embedded in the upper region of the projection 32 as particularly shown in FIGURE 7. A transversely extending tang 64 extends generally rearwardly of the vertical portion 58 of the wear plate and during the molding of the section 18, is embedded in the thickened portion 28 of the handle component 18 as shown in FIGURE 7.

The portions 58, 60 and 64 of the wear plate 56 are respectively provided with circular openings 66, 67 and 68 which, during the molding operation of the handle component 18, the offset portion 30 and the projection 32, become filled with the plastic material of which the handle is molded forming sprues of plastic in the openings serving to prevent dislodgment of the wear plate 56 and securely hold the same in embedded position.

The faces or outer surfaces of the horizontal portion 60 and the vertical portion 58 provide metal surfaces engaging a carton and serving to prevent wear of the gaging means when the instrumentality is employed in the manner shown in FIGURE 9.

FIGURES 9, 10 and 11 illustrate positions of use of the carton severing instrumentality of the invention. With particular reference to FIGURE 9, the instrumentality is shown in a position to sever the upper side wall regions of a carton 72.

In utilizing the cutter for this purpose, the blade 34 is moved to extended or projected position by manipulating the knurled nut 50 and moving the bolt 46 and the blade in a lefthand direction as viewed in FIGURE 2 until the blade is fully extended, after which the knurled nut 50 may be drawn up to hold the blade in a projected position of use. The operator positions the cutting instrumentality with the projecting gage block 32 over the top surface of the carton or package which brings the horizontal portion 60 of the wear plate 56 in engagement with the top surface 70 of the carton 72 and the outer surface of the vertical portion 58 of the wear plate in contact with the adjacent side wall of the carton as shown in FIGURES 2, 9 and 11.

The operator then draws the cutting instrumentality in a horizontal direction with the blades 34 projecting through the carton wall and severs all four side walls of the carton 72, while maintaining the gage block 32 in engagement with the top surface 70 until the carton is completely severed at the line 74 shown in FIGURE 9. This completely disengages the upper region of the carton, the upper or severed portion of the carton forming a flanged tray-like member.

After this operation is completed, the operator inverts the cutting instrumentality to the position shown in FIGURES 1 and 10 with the lower or bottom surface 33 of the gage block 32 in contact with a table or other means 75 supporting the carton 72. The blade 38 is then moved forwardly of the handle to a projected position of use by manipulating the knurled nut 52 and sliding the bolt 48 forwardly in its slot, and the blade locked in projected position by drawing up the nut 52 on the bolt 48.

The operator then grasps the handle portion 12 and draws the cutting instrumentality around the four sides of the carton, while maintaining the surface 33 of the gage block 32 in contact with the table, effecting a severing of the carton at the line indicated at 76 which operation forms a tray of the lower section of the carton. The two severing operations completely separate the upper and lower tray-like portions of the carton from the intermediate band 78. After the second severing operation is completed, the operator removes the upper tray-like section of the carton together with the upper tier of cans 80, leaving the lower tier 82 of the group of cans in the lower tray portion of the carton.

The intermediate band 78 of the carton which has been severed from the top and bottom sections is discarded. Thus as a result of the two cutting operations the carton is transformed into two tray-like portions each of which contains a tier of can goods previously packaged in the carton. The zones of cutting or lines of cutting the carton indicated at 74 and 76 are preferably equidistant respectively from the top and bottom outer surfaces of the carton.

With particular reference to FIGURE 3, the distance designated (a) from the lower surface 33 of the gage block 32 to the cutting edge of the blade 38 is the same as the distance (a') from the upper surface of the horizontal portion 60 of the wear plate 56 to the second cutting plate 34. Thus by fabricating the construction whereby the thickness of the gage block 32 is equal to the vertical distance between the cutting edges of the blades 34 and 38, the flanges on the tray-like portions of the carton resulting from the severing operations will be of the same height.

It is to be understood however that if the flanges of the upper and lower tray portions provided by the severed carton are to be made of different heights, the distances (a) and (a') will not be identical. FIGURE 11 illustrates the position of the gage block 32 in contact with the upper surface 70 of the carton and the cutting blade in a projected position of use extending through the carton wall for effecting severing of the carton wall along the line 74.

It will be noted from FIGURE 11, that the offset portion 30 is made of hollow configuration and is defined by comparatively thin wall portions 31 as shown in FIGURE 11 to reduce the weight of the cutting instrumentality. With particular reference to FIGURE 2 it will be noted that the obverse region of the gage block 32 is cored out and provided with reinforcing webs 35 for the purpose of reducing the weight of the device without sacrificing strength characteristics of the gage block.

FIGURES 13 through 15 illustrate a modified form of construction wherein a resilient means is incorporated in the arrangement for biasing the cutting blades in one direction. In this form of the invention, the handle portion 12', the gage block 32' and the head portion 10' are generally the same shape as the corresponding components in the form of the invention illustrated in FIGURES 1 through 11.

The section 90 of the handle section 18' and the forward portion of handle section 16' is provided with pairs of longitudinally extending slots 92 and 94, shown in FIGURE 15, the slots accommodating respectively the rod-like members or pins 96 and 98 shown in FIG-

URES 14. The portion 100 of the handle section 16' is provided with a longitudinally extending slot to slidably accommodate a cutting blade 102 which is guided in its sliding movements by means of metal inserts 104 embedded in the plastic material of the handle as shown in FIGURE 14.

The portion 106 of the handle section 16' is formed with a recess in which is slidably mounted a second cutting blade 108 which is guided in its sliding movements by means of metal inserts 110 shown in FIGURE 14. Each of the cutting blades 102 and 108 is of slightly greater length than the blades 34 and 38 and each is provided with a circular opening similar to the opening 49 shown in FIGURE 12 to respectively accommodate the bolt-like members or pins 96 and 98. The parallel slots 92 and 94 accommodate slidable movements of the rod-like members 96 and 98 for moving the blades longitudinally in their slots.

Disposed between the rods or members 96 and 98 and the end walls 112 of the sections 100 and 106 are expansive coil springs 114 and 116. The springs 114 and 116 normally bias the cutting blades 102 and 108 to their out-of-use positions within the portions 100 and 106 viz. the blades being biased in a right-hand direction as viewed in FIGURE 13. The upper region of the rod 96 is provided with a transverse threaded opening which receives a threaded tenon portion 118 formed on a shaft or pin 120, the latter extending transversely through a slot 122 elongated lengthwise of the handle.

The shaft or pin 120 extends laterally from the handle structure and is threaded to accommodate a knurled nut 124. The outermost end region of the shaft 120 is provided with a flange head 126 which limits the outermost threaded movement of the nut 124 with respect to the shaft 120.

When the nut 124 is backed away from engagement with the side surface of the section 100, the expansive spring 114 is free and biases the blade 102 in a right-hand direction, as viewed in FIGURE 13, to its retracted or out-of-use position.

When the nut 124 is in its non-locking position, that is, in engagement with the flange or head 126 on the shaft 120, the operator is enabled to exert finger pressure forwardly upon the nut 124, moving the rod 96, the shaft 120 and the blade 102 in a left-hand direction as viewed in FIGURE 13 whereby the blade is projected beyond the end of the portion 100 to a position of use whereby a carton wall may be severed by the blade 102.

If the operator desires to lock the blade in a projected position of use, the nut 124 may be drawn up while in the broken line position indicated in FIGURE 13, the spring 114 being then held in compressed condition. When it is desired to retract the plate 102 the operator loosens the knurled nut 124 and the expansive pressure of the spring 114 retracts the blade into the handle portion. The rod 98 is provided with a transverse threaded bore to accommodate a threaded tenon 130 formed on the end of a pin or shaft 132 which extends through a slot 134 elongated lengthwise of the handle.

The shaft 132 is provided with a threaded portion accommodating a knurled nut 136, the outer end of the shaft 132 being formed with a flange or head 138. The construction or shaft 132, nut 136 and head 138 are of the same construction for manipulating the blade 108 as the shaft 120, nut 124 and head 126 effects manipulation of the blade 102.

Thus, the operator by maintaining the nut 136 in a loosened position may, by forwardly directed finger pressure applied to the nut, effect compression of the spring 116, moving the blade 108, rod 98 and shaft 132 forward to project the blade to a position of use as shown in broken lines in FIGURE 13. By drawing up the nut 136, the blade may be locked in either a projected posi-

tion of use or retracted position within the handle structure.

If desired, an abutment may be provided at the rear ends of the slots 92 and 94 in the handle construction and springs disposed between such an abutment and the rods 96 and 98 respectively whereby the blades may be normally resiliently biased to a projected position of use and may be retracted by manipulation of the knurled nuts 124 and 136 in a rearward direction toward the handle to lock the plates in retracted or out-of-use positions 10 with the springs under compression.

From the foregoing it will be seen that in the several forms of the invention, the cutting blades may be selectively moved from a retracted to a projected position and locked in either position. In the form shown in FIGURES 13 through 15, the plates are normally biased to a retracted or out-of-use position but may be readily projected to a position of use by forwardly directed finger pressure exerted upon the knurled nuts 124 and 136.

With the nuts in a loosened position, the operator may effect severing operations by maintaining finger pressure in a forward direction upon the knurled nuts without drawing up the nuts into blade locking position so that immediately upon release of finger pressure on the nuts, the blades will be automatically retracted into the handle portion under the influence of the springs.

It is apparent that, within the scope of the invention, modifications and different arrangements may be made other than as herein disclosed, and the present disclosure is illustrative merely, the invention comprehending all variations thereof.

I claim:

1. A carton severing instrumentality including, in combination, a handle construction formed at one end region with a recess, a cutting blade disposed in said recess, registering openings formed in said blade and handle construction, means extending through said openings for maintaining said cutting blade in the recess, said handle construction being resinous material and having a laterally extending portion, a gage block projecting from said laterally extending portion, said gage block having a gaging surface arranged in a plane parallel with said cutting blade, said cutting blade being arranged to project beyond the handle construction for engagement with a carton to be severed, and a metal member secured to a surface of said gage block and a surface of said laterally extending portion arranged to engage the carton to be severed.

2. A carton severing instrumentality including, in combination, a handle construction formed at one end region with a recess, a cutting blade disposed in said recess, registering openings formed in said blade and handle construction, means extending through said openings for maintaining said cutting blade in the recess, said handle construction having an offset portion, and a gage block projecting from said offset portion, said gage block having a gaging surface arranged in a plane parallel with said cutting blade, said cutting blade being arranged to project beyond the handle construction for engagement with a body to be severed, said handle construction being resinous material, and a metal member embedded in a surface of said gage block and a surface of said offset portion arranged to engage the carton to be severed, and resilient means enclosed within the handle construction normally biasing the cutting blade in one direction.

3. A cutting instrumentality including a body formed with a head portion and a first handle section, a second handle section mating with said first handle section, means securing the handle sections together, transversely spaced recesses formed in one of said handle sections, said recesses being elongated lengthwise of said handle, said recesses being arranged in spaced parallel planes, cutting blades disposed for slidable movement in said recesses,

means engageable with said blades and extending exteriorly of one of the handle sections for manually moving the blades along the recesses, means for locking said manually operable means to secure the blades in any position of adjustment, said head portion including a gage block having gaging surfaces on opposite faces of the block and arranged in planes parallel with the planes of the blades, the distance between one of said gaging surfaces and one of the blades being substantially equal to the distance between the other of the gaging surfaces and the other blade.

4. A cutting instrumentality for severing cartons including a handle construction formed of two mating handle sections of plastic material, means for securing the handle sections together, one of said handle sections being formed with laterally spaced recesses arranged in spaced planes and extending lengthwise of the handle construction, metal insert means in each of said recesses, a cutting blade disposed within each of the insert means, said insert means forming guides for accommodating slidable movement of said blades, elongated passageways formed in said handle sections adjacent said blades, members extending through openings in said blades and into said passageways and arranged to be manually moved to positions to project the blades from the handle sections and retract the blades into the handle sections, one of said handle sections being formed with an offset portion, a gage means provided on said offset portion, and a metal plate on said gage means providing a gaging surface, said gaging means having a second gaging surface in parallelism with the gaging surface provided by the metal plate.

5. A cutting instrumentality for severing cartons including a handle construction formed of two mating handle sections of plastic material, means for securing the handle sections together, one of said handle sections being formed with laterally spaced recesses arranged in vertically spaced planes and extending lengthwise of the handle construction, metal insert means in each of said recesses, a cutting blade disposed within each of the insert means, said insert means forming guides for accommodating slidable movement of said blades, elongated passageways formed in said handle sections adjacent said blades, bolts extending through openings in said blades and into said passageways and arranged to be manually adjusted to positions to project the blades from the handle sections and retract the blades into the handle sections, one of said handle sections being formed with an offset portion, a gage means provided on said offset portion, a metal plate on said gage means providing a gaging surface, said plate being embedded in the plastic material, said gaging means having a second gaging surface in parallelism with the gaging surface provided by the metal plate, the distance between the gaging surfaces being substantially equal to the space between the planes of the blades, and means cooperating with said bolts for locking said blades in adjusted positions.
